LINE SETTING DEVICE FOR FLAT
WRITING MACHINES

Rodolfo Fierz, Buenos Aires, Argentina

Application December 16, 1933, Serial No. 702,749
In Germany December 24, 1932

7 Claims. (Cl. 197—2)

The invention relates to a device on flat writing machines, particularly electrically actuated Elliott-Fisher machines, for copying book-keeping for the automatic setting of the slide carrying 5 the types to the line to be written upon of the day total sheet to be placed undermost.

Flat writing machines are known wherein the carriage carrying the type slide and moved backwards and forwards by an electric motor is held 10 by a stop, adjusted by hand, on the line to be written upon, whilst the motor is stopped simultaneously.

The novelty resides therein that the setting of 15 the stops is not effected by hand but is effected automatically by the type slide, the setting of the stop being effected positively line by line when the type slide is set in the left hand initial position on the line. When setting the stop by the spacing of a line the carriage is also locked so 20 that this remains stationary on the line. The carriage is returned in the known manner into its initial position at the upper end of the written document, when the type slide reaching the end of the line sets a stop. The movement of the 25 carriage on to the last written line by the electric motor in a novel manner by a hand actuated rod, whilst the type slide is always at the right of the line commencing position so that the movement of the stop by a line spacing, is only effected by 30 the return movement into the initial position.

The device has the advantage that the type slide automatically finds its correct position on the document to be written upon and always remains locked in the operative position. The hitherto usual release devices for the motor actuated by the knees are omitted. There is also omitted the work of accurate adjustment of the carriage on the line. By adjusting the type slide in its initial position there is obtained the line spacing 40 and the locking in the new operating position.

The device may also be applied subsequently to existing machines.

In the accompanying drawings is illustrated by 45 way of example one form of construction of the subject of the invention, wherein:

Fig. 1 shows a front elevation and

Fig. 2 shows a plan of the device applied to a writing machine.

Fig. 3 shows a part of the device to a larger scale.

Fig. 4 is a section on the line IV—IV of Fig. 3.

Fig. 5 is a section on the line V—V of Fig. 3.

Fig. 6 is a section on the line VI—VI of Fig. 3.

Fig. 7 and 8 show details.

Fig. 9 shows the parts of Fig. 3 in another position.

Fig. 10 shows a further part of the device to a larger scale.

Fig. 11 is a plan of Fig. 10.

Fig. 12 is a section on the line XII—XII of Fig. 10.

Figs. 13—16 show details.

In Figs. 1 and 2 there is shown diagrammatically and by chain-dotted lines a known electrically driven flat writing machine of the Elliott-Fisher system. To the carriage R, longitudinally movable on the table T, are secured two bearing plates 1 and 2 in which is mounted a rod 3. The latter is provided at one end with a pin 4 engaging with a hole in an actuating member 5. A pin 6 provided on the member 5 projects into the cam track 7 of a stationary guide member. The member 5 is also provided with a projection 9 which is located in an opening 10 (Figs. 3 and 9) of the bearing plate 1. On the bearing plate 1 is also pivotally mounted a double-armed lever 14 provided with a roller 12. Into an aperture of the lever 14 there projects a pin 15 of a lever 16 which at its other end rests in a bearing head 17 (Figs. 3, 8, 9). A spring 18 normally tends to draw 16 towards the left (Fig. 3). As a security against this movement the lever 16 is provided with a projection 20 which bears against a projection 21 of a spring actuated bell crank lever 22. To one end of the latter is secured a pull rod 23 which is connected to a lever 24 (Figs. 2, 3, 8). This lever is mounted in a stop member 25, secured to the carriage R and serving for the purposes hereinafter described. On the bearing plate 1 is also mounted a double-armed lever 27 (Figs. 2, 3, 9) of which one end is forked and engages with a guide roller 28 which latter is keyed to a shaft 29. One end of the shaft 29 carries the pulley 30 which is driven in the known manner by an electric motor not shown in the drawings and serves to reverse the movements of the carriage R.

Into the other end of the rod 3 is screwed an extension member 3' which is secured in position by a nut. In this manner the length of the rod 3 can be adapted accurately to the width of the writing machine. The extension 3' is prevented from turning by a groove 32 with which there engages a projection 33 on the bearing plate 2. The extension 3' is provided with a notch with which engages a spring actuated locking plate 34. To the bearing plate 2 is hinged a lever 35 having a projection 36 engaging with the locking plate 34 and on which there is pivotally 55

mounted a further lever 31. This lever 31 is provided with a projection against which there bears the end of a rod 40 provided with teeth 39 (Figs. 10, 11). The other end of the rod 40 is 5 provided with a head 41 (Figs. 1, 2).

The rod 3 is under the action of a spring 43 which tends to move the rod towards the right (Figs. 1-4, 10, 11). To the rod 3 is also hinged a lever 44 (Figs. 10, 11) which in turn is connected 10 to one end of a double-armed lever 45. The latter is mounted on a plate 46, rigidly connected to the carriage R. The other end of the lever 45 carries a roller 47. On the plate 46 is also mounted a bell crank lever 48 (Fig. 11) of which 15 one end carries a roller 49, whilst the other end is connected to a pull rod 50.

Laterally of the table T is located a rail 52 (Figs. 1, 2, 3) carrying a rack 53. On this rack 53 is movably mounted a slide 54 (Figs. 3, 5, 6, 7). 20 With a slot of the latter there engages a pawl 55 which is held in the position shown in Fig. 5 by a spring 56. A key 57 is held in the raised position by a projection 58 of the pawl 55 (Fig. 5). A stop member 61, secured by screws 60, is 25 mounted movably on the slide 54, the member 61 being forced into the position shown by the springs 62. In the slide 54 there is also mounted a spring actuated projection 63 (Figs. 3, 7) which is in connection with one end of a double- 30 armed lever 64. The latter carries a pin 65.

The key 57 projects into the path of a lever 67 (Figs. 1, 2, 15, 16) hinged to a plate 68. The latter is secured at the bottom to the slide S, provided with the writing keys and trans- 35 versely movable in the carriage R. On the same plate 68 there is also rotatably mounted an arm 69 (Figs. 1, 2, 13, 14) which at one end has an arm 70 and at the other end a bent portion 71.

To the rack 53 there is pivotally connected by 40 means of links 72 (Figs. 3, 5) a rod 73 which extends parallel to the rack 53 and at the front is provided with a head 74. The rod 73 is held in the position shown in Fig. 2 by a spring 75.

The method of operation is as follows:—

45 The rest position of the writing machine is shown in Fig. 2. The sheet B to be written upon, for example the journal sheet or the day total sheet, and over this the account sheet, the monthly account and so forth with the carbon paper and so forth, is placed on the table and clamped in the usual manner. Pressure is then applied to the head 74 of the rod 73 whereby the latter is rocked outwardly and moves away from the rack 53 (Fig. 9). Consequently the lever 24 bearing against the rod 73 makes a rocking movement. The pull rod 23 rocks the bell crank lever 22 against the action of its spring until the projection 21 releases the projection 20 of the lever 16. The latter, under the action of its spring 18, 50 snaps to the left (Figs. 3, 9) and is raised simultaneously as a projection thereof runs over the surface 78 of the bearing head 17. A pin 80 of a rod 81 is thus caused to pass into the notch 79 of the lever 16; the rod 81 is thus drawn to the left (Figs. 3 and 9). The other end of the rod 81 is connected to the lever 27. The lever 27 is rocked into the position shown in Fig. 9 and thus moves the shaft 29 to the right, so that the pulley 30 is engaged and the carriage R moves 55 forwardly with the slide S (Fig. 2). At the same time the lever 16 has also rocked the lever 14 with the roller 12. The slide 54 has previously been set, in the exact position relatively to the sheet B, on the rack 53. The carriage R moves 60 forwardly until its stop member 25 (Figs. 2, 9) 50

strikes against the projection 83 of the stop member 61, the springs absorbing the shock. The projection 63, which has been forced back by the stop member 25, again projects from the slide 54 and engages behind the stop member 25. 5 The carriage R is held immovably. At the same time the roller 12 has run on to the cam surface 84 of the stop member 61, whereby the lever 14 has drawn the lever 16 back into its rest position (Fig. 3). As a result also the rod 81, the lever 27 10 and shaft 29 have been returned into their original position, and the pulley or gear 30 is disengaged. The slide S is exactly at the line of the sheet B to be written upon. In order to advance the carriage when writing a fresh line the slide 15 S is moved to the left by the known means and in the known manner. The lever 67 passes the key 57 and depresses it for a short time. The pawl 55 is thus rocked (Fig. 15) and is disengaged from the teeth of the rack 53 in order to engage 20 immediately with the next tooth as in the meantime the carriage R has been advanced automatically.

When the slide S has reached the end of the line the end 70 of the arm 69 strikes against a 25 previously adjusted stop 86 (Fig. 10) provided on the writing machine and is depressed. As a result the part 71 of the arm 69 engages with the teeth of the rod 40 and moves the latter to the right against the projection 38 of the lever 37 30 which in turn rocks the lever 35. The latter by means of its projection 36 disengages the plate 34, against the action of its spring, from the notch of the extension 3'. The rod 3 and the extension 3' are immediately moved to the right 35 by the spring 43 (Fig. 2). The actuating member 5, provided at the other end of the rod 3, moves in the slot 10 and in the cam track 7 in such a manner that the projection 9 engages with the pin 87 of the lever 27 and rocks this into the 40 position indicated by II (Fig. 3) whilst simultaneously moving the shaft 29 to the left. The gear or pulley 30 is engaged for reverse movement and the carriage R again moves rearwardly into the position shown in Fig. 2. The stop 25 of 45 the carriage, which has been held locked between the parts 63 and 83, is released simultaneously in that during the movement of the shaft 29 to the left the roller 90 keyed thereto abutted against the pin 65 and rocked the lever 64. The projection 63 was thus retracted.

At the rear of the table T are provided two stops 91, 92. The roller 49 first runs on to the stop 91 and by means of pull rod 50 actuates a known release device which releases the slide S, 55 which then moves to the left up to a stop. As soon as the roller 47 of lever 45 comes into contact with the stop 92 the rod 3 is again moved into its rest position shown in Figs. 1-4, 10, 11 by means of the levers 45 and 44. At the same 60 time the lever 27 is rocked into its mid position (Fig. 3) thus immediately disengaging the gear 30. The writing machine is thus again in its starting position.

By pressing the head 41 of the rod 40 65 vision is made for allowing the carriage R to move rearwardly at any time independently as to whether the slide S has reached its right hand end position.

When the carriage has reached its rear position 70 the sheets (account sheets, copies and eventually also the journal sheet) can be exchanged.

What I claim is:

1. In a flat writing machine the combination 75 of a carriage, a type slide on said carriage,

clamping means for the paper to be written upon in said machine, means for actuating said carriage to move the same over said paper, an adjustable stop for limiting the movement of the carriage, means for disengaging said actuating means automatically when the carriage reaches said stop, a rack in said machine on which said stop may be moved and locked, operating elements associated with said stop, said slide being adapted through the medium of said operating elements to release said stop from its locked position and to move through a line spacing when the said slide is moved to the beginning of a line, bearings on said carriage, a rod mounted in said bearings for sliding movement therein, and mechanism between said rod and said actuating means, for moving said rod to engage and disengage said actuating means.

2. In a flat writing machine the combination of a carriage, a type slide on the carriage, clamping means for the paper to be written upon in said machine, means to actuate said carriage to move the same over said paper, an adjustable stop to limit the movement of the carriage, means for disengaging said actuating means automatically when the carriage reaches said stop, a rack in said machine on which said stop may be moved and locked, a rail by which said rack is carried, a block mounted on said rack, a pawl mounted on said block, a spring to hold the pawl in locked position on the rack, a key mounted in said block, said key being adapted to release said pawl from locked position with said rack, a spring between said block and said stop, a projection on said stop, a sliding pawl mounted in said stop, a second stop member on said carriage, said second stop member being adapted to engage between the projection on the first mentioned stop member and the sliding pawl in the locked position of the carriage.

3. In a flat writing machine, a carriage, a type slide on said carriage, clamping means for the paper to be written upon in said machine, means for actuating said carriage to move the same over said paper, an adjustable stop for limiting the movement of the carriage, means for disengaging said actuating means automatically when the carriage reaches said stop, a rack in said machine on which said stop may be moved and locked, a rail by which said rack is carried, a block mounted on said rack, a pawl mounted on said block, a spring to hold the pawl in locked position on the rack, a key mounted in said block and adapted to release said pawl from its locked position with said rack, a spring between said block and said stop, a projection on said stop, a sliding pawl mounted in said stop, a double-armed lever pivotally mounted on said stop, one arm of said lever being adapted to co-operate with said sliding pawl, a pin on the other arm of said lever, a roller on said carriage, said roller being adapted to cooperate with said pin, a second stop member on said carriage, said second stop member being adapted to engage between the projection on the first mentioned stop member and the sliding pawl in the locked position of the carriage.

4. A flat writing machine according to claim 1 including a rail, by which the rack is carried, and in which the operating elements include a block mounted on said rack, a pawl mounted on said block, a spring to hold the pawl in locked position on the rack, and a key mounted in said block, said key being adapted to release said pawl from its locked position with said rack, a

spring between said block and said stop, a projection on said stop a sliding pawl mounted in said stop, a projection on said slide, said projection on the movement of the slide for setting actuating said key so as to disengage said pawl from said rack, a second stop member on said carriage, said second stop member being adapted to engage between the projection on the first mentioned stop member and the sliding pawl in the locked position of the carriage. 10

5. In a flat writing machine, the combination of a carriage, a type slide on said carriage, clamping means for the paper to be written upon in said machine, means for actuating said carriage, said carriage being adapted to be moved over said paper by said actuating means, an adjustable stop for limiting the movement of said carriage, means for disengaging said actuating means automatically when the carriage reaches said stop, a rack in said machine, said stop being capable of being moved and locked on said rack, operating elements associated with said stop, said slide having means coacting with said operating elements to release said stop from its locked position and to move through a line spacing when the said slide is moved to the beginning of a line, an arm pivotally mounted on said type slide, an adjustable stop in said machine, said adjustable stop being adapted to co-operate with said arm, said arm having a bent end, a sliding rack mounted in said carriage, said bent end being adapted to co-operate with said rack, a rod mounted on said carriage, locking means for said rod, a spring connected to said rod, said spring normally urging said rod in one direction, a pivoted lever operatively connected to said rod, said lever co-operating with said actuating means, and means whereby the rack, moved releases the rod so that when the rod is moved by its spring it moves the actuating means for moving the carriage in the reversed direction. 40

6. In a flat writing machine, the combination of a carriage, a type slide on said carriage, clamping means for the paper to be written upon in said machine, means for actuating said carriage, said carriage being adapted to be moved over said paper by said actuating means, an adjusting stop for limiting the movement of said carriage, means for disengaging said actuating means automatically when the carriage reaches said stop, a rack in said machine, said stop being capable of being moved and locked on said rack, operating elements associated with said stop, said slide having means coacting with said operating elements to release said stop from its locked position and to move through a line spacing when the said slide is moved to the beginning of a line, a rail, links pivoted to said rail, a rod connected to said links, link mechanism associated with said rod, and mechanism for moving said actuating means, said mechanism being operated by said link mechanism. 55

7. In a flat writing machine, the combination of a carriage, a type slide on said carriage, clamping means for the paper to be written upon in said machine, means for actuating said carriage, said carriage being adapted to be moved over said paper by said actuating means, an adjustable stop for limiting the movement of said carriage, means for disengaging said actuating means automatically when the carriage reaches said stop, a rack in said machine, said stop being capable of being moved and locked on said rack, operating elements associated with said stop, said slide having means coacting with said op- 75

erating elements to release said stop from its locked position and to move through a line spacing when the said slide is moved to the beginning of a line, a pair of stops on said machine, a pair of pivoted levers mounted on said carriage, rollers on said levers, the roller on one lever being adapted to cooperate with one of said stops to stop forward movement of the carriage, the roller on the other lever being adapted to cooperate

with the other stop to stop said actuating means, a rod slidably mounted in said carriage, a forked lever mounted on said carriage, and adapted to be actuated by said rod and cooperating with said carriage actuating means, the second named lever of said pair of levers being operatively connected to said rod. 5

RODOLFO FIERZ.
